UNITED STATES PATENT OFFICE.

ROBERT AERNOUT BARON VAN LYNDEN, OF Utrecht, NETHERLANDS, ASSIGNOR, BY
MESNE ASSIGNMENTS, TO AMERICAN THERMOPHONE COMPANY, OF BOSTON,
MASSACHUSETTE, A CORPORATION OF MASSACHUSETTS.

THERMOTELPHONE TRANSMITTER AND RECEIVER.

Application filed March 12, 1918. Serial No. 222,016.

To all whom it may concern:

Be it known that I, ROBERT AERNOUT BARON VAN LYNDEN, a subject of the Queen of the Netherlands, and resident of Utrecht, in the Province of Utrecht and Kingdom of the Netherlands, have invented certain new and useful Improvements in Thermotophone Transmitters and Receivers, of which the following is a specification.

10 It is well-known that so-called thermophones, that is to say, thermo-telephone transmitters and receivers embody in their structure a number of extremely thin conductors, or "hot wires," usually shaped as small bows or loops standing erect and secured to a support or carrier. With wire loops of the same cross section, the electric energy consumed by each bow or loop depends on its length, and this energy in turn, 20 in the case of a thermo-telephone, determines the loudness of sound-reproduction.

On the other hand, in order to obtain a satisfactory or most efficient sound-reproduction, it is necessary that a certain amount 25 of electric energy be developed in the hot wires in the form of Joule-heat. From this it follows that, for a given cross section of the hot wire, there is a definite length at which the sound-reproduction results will 30 be best.

However, mechanical conditions as well as electrical ones affect the results. If for instance the bow or loop is made too high, it becomes too weak or slack, and will be liable to lean or fall over to one side, in which inclined position it may come in contact with an adjacent bow or loop. No great harm would result from this if such contact always took place at equipotential 35 points of the different loops, but in practice it cannot very well be avoided that such contact should occur, at times, between points of different potential. In this event one of the loops would become over-loaded, since 40 the loops are connected in parallel, and the loop thus receiving an excess of current would become incandescent, and the intermittent contact resulting therefrom would impair the correct reproduction of the sound. The danger of mutual contact just referred to might indeed be avoided by spacing the loops farther apart, but this would be objectionable, both on account of the increased size of the apparatus, which would 45 make it less convenient in use, and on ac-

count of the fact that sound-reproduction is poorer in large apparatus or containers than in small ones.

To overcome the difficulties pointed out above, I employ a certain novel construction, an example of which is illustrated by the accompanying drawing, which shows a longitudinal section of the device.

In carrying out my invention, I make the hot wire A of a thermo-telephone receiver or transmitter with a thin coating or skin B of insulating material, so that adjacent loops may touch each other without affording a new path to the electric current. The application of such skin or coating may be performed in various ways, as by dipping the bows or loops into a suitable bath, by heating them to produce a superficial oxidation, by the "Schoop" spraying process, or in any other suitable manner, as long as the treatment results in the production of a fine skin or coating of satisfactory insulating power and of proper resistance to the effects of the temperature to which the hot wire is subjected during the operation of the thermophone.

Practical trials have shown that the presence of an insulating skin or coating made according to my invention does not affect the sound-reproducing properties of the hot wire.

Among the numerous advantages of my invention, there is, first, the fact adjoining loops or bows may touch each other without causing trouble by short-circuiting, and from this it follows that the loops may be placed closer together than according to present constructions, where the loops are placed at a relatively considerable distance from each other, in order to minimize the danger of contact; the reproduction of the sound is improved by the arrangement of the wire loops close to each other, the size of the container C remaining unaltered.

When the container C is made of metal or other conductor of electricity, and the loops might come in contact with the container, it is desirable, for additional safety, to apply an insulating coating C' of the character referred to, upon those parts or surfaces of the container which are liable to be engaged by the loops.

It is not necessary that the coating be non-conductive at the time of its formation or application, since I may apply a con-

ducting coating and convert it into a non-conducting one. For instance, I may deposit on the hot wires, by electrolysis, an extremely fine coating of a suitable metal, say copper, and while this coating will be conducting at first, the heat developed in the wire during the operation of the apparatus will quickly convert the copper or other metal into a non-conducting oxid, efficient to form an insulating sheath or protector for the purposes of my invention.

Another important advantage of my invention resides in the possibility of using non-precious metals for the hot wire, which hitherto has always been made of precious metal (platinum). The insulating coating or skin, whether formed by superficial oxidation or otherwise, will prevent access of the surrounding air to the hot wire proper, so that no oxidation of the core or hot wire proper need to be feared. The wider choice of materials available for the hot wire is a great advantage of my invention, since the materials employed hitherto are not always as efficient as might be desired, and in particular, the character of transmission is often rather poor on short lines. The reason for this is found in the fact that, in a short line, the resistance of the thermo-telephone is comparatively large in relation to the resistance of the line. The materials used hitherto for the hot wires, viz.: precious metals, have a positive temperature-coefficient, that is to say, their specific resistance increases with the current-density, and thus, the heating effect still further increases the proportion which the resistance of the thermo-telephone forms of the total resistance (telephone and line), thus accounting for the comparatively unfavorable results often observed on very short lines. The tops of the current-oscillations or current-waves are flattened by this increased resistance, and this alteration of the waves is prejudicial to the purity of the sound reproduced. Among non-precious metals, however, there are some (for in-

stance the alloy known as "constantan") the temperature-coefficient of which is practically negligible, that is to say, their specific resistance is not affected materially by the increase in temperature, hence the possibility of using non-precious metals is an advantage not only on account of the relative cheapness of such metals, but for the reason that, by the employment of materials having a low or negligible temperature-coefficient, a material improvement in sound-reproduction may be obtained, particularly on short lines.

Various modifications may be made without departing from the nature of my invention as set forth in the appended claims.

I claim:

1. A thermophone, provided with a hot wire having an insulating coating in contact with atmospheric air.
2. A thermophone, provided with a hot wire having an insulating coating, and a container for said hot wire having an insulating coating at the point or points liable to come in contact with said hot wire.
3. A thermophone, provided with a metallic hot wire having a fine coating of a metal in contact with atmospheric air adapted to become superficially oxidized upon the heating of such wire.
4. A thermophone, provided with a hot wire having a fine coating of copper in contact with atmospheric air.
5. A thermophone, provided with a hot wire made of a material having a practically negligible temperature-coefficient, and coated externally with an insulating material in contact with atmospheric air.
6. A thermophone, provided with a hot wire, and a conducting container for said hot wire, said container having an insulating coating at the point or points liable to come in contact with said hot wire.

In testimony whereof I have hereunto set my hand.

ROBERT AERNOUT BARON van LYNDEN.
